WALL CONSTRUCTION

George H. Lenke, Elmhurst, Ill., assignor of one-half to Julius J. Ohlis, Oak Park, Ill.

Application July 31, 1940, Serial No. 348,842

13 Claims. (Cl. 72—42)

This invention relates to wall construction wherein one or more individual panels may be provided, the invention having for its object to provide a construction which is simple in parts, efficient in use, and less costly to manufacture than those heretofore proposed.

With these and other objects in view the invention resides in the novel details of construction and combinations of parts as will be disclosed more fully hereinafter and particularly pointed out in the claims.

Referring to the accompanying drawings forming a part of this specification and in which like numerals designate like part in all the views—

Fig. 1 is a diagrammatic representation of the employment of a plurality of the panels in a wall construction;

Fig. 2 is a partial perspective view on a greatly enlarged scale of an interlocked relationship between the upper corners of two adjacent panel frames;

Fig. 3 is a foreshortened perspective view of a complete panel frame;

Figs. 4 and 5 are enlarged detail sectional views illustrating the tying together of two adjacent panel frames, said views taken as on the lines 4—4 and 5—5 respectively of Fig. 3 and looking in the direction of the arrows;

Fig. 6 is a fragmentary enlarged detail sectional view illustrating the securement of two building blocks in adjacent panels, said view taken as on the line 6—6 of Fig. 2 and looking in the direction of the arrows;

Figs. 6a and 6b are views showing modifications of construction of the locking strip;

Fig. 7 is an enlarged detail sectional view taken as on the line 7—7 of Fig. 2 and looking in the direction of the arrows;

Fig. 8 is a detail view partly in section and partly in elevation illustrating the joint between the horizontal and vertical locking strips employed for securing the blocks in their panels;

Fig. 9 is a view similar to Fig. 6 but illustrating a modification of the block securement shown therein; and

Fig. 10 is a vertical sectional view of the wall construction taken as on the line 10—10 of Fig. 1 and looking in the direction of the arrows.

This invention may be applied to a single panel employed in the construction of a building wall, or to a plurality of similar panels laid adjacent to each other in such wall construction, the single or individual panel comprising a metallic frame of rectangular or other polygonal shape and with- in which a building block preferably of glass is

secured in such manner that should the block be broken it may readily be replaced, said block being retained in its frame by locking strips disposed along the perimetric edges of the block, said strips snappingly engaging anchor clips or springs associated with the frame. In Fig. 3 is shown one of such panel frames; in Fig. 2 is shown the means employed for locking together two sidewise adjacent and similar panel frames; and in Fig. 1 is indicated the association of a plurality of such panel frames to form a relatively large area of glass wall construction made in accordance with this invention.

Referring to Fig. 3 the panel frame is illustrated as comprising a plurality of serially connected frame members, in this instance forming a rectangular frame having the upper frame member 2, the lower frame member 3, and the side frame members 4 and 5, made of suitable flat sheet metal and preferably having cut-outs indicated at 6 to reduce the weight of the frame.

Intermediate the ends of each frame member, and preferably at the approximate middle thereof, there is an integral cross-web indicated at 7 for strengthening the frame member, and in the inner face of each web there is formed a groove 8 for receiving one leg such as 9 of a substantially U-shaped clip indicated by the numeral 10 (see Figs. 4 and 5), the other leg 11 of said clip engageable with a similar groove 8 in a similarly located web of another adjacently positioned frame. Thus it will be understood, from the example illustrated in Figs. 4 and 5, that when two similar panel frames are laid in adjacent registry with each other, a web of one frame will be registered with a web of the other frame, and that a clip 10 may be frictionally applied to the grooves of the two registered webs to secure the two frames together, the legs of said clip lying wholly within said grooves to provide an unobstructed flat inner surface in each frame for the reception of its glass block.

At each end of the top frame member 2, and extending transversely of said member or in a direction parallel to the web 7, there is formed in the outer surface of said frame member a groove such as 15 spaced from the extreme corner edge of the frame to provide an upstanding or outwardly directed rib such as 16, and along the substantial middle of this groove but spaced from each longitudinal edge of the frame is an upstanding pin such as 17. Likewise, at each end of the bottom frame member 3 there is formed in the outer surface thereof a correspondingly similar groove such as 18 providing the similar ribs such as 19, and

along the substantial middle of each groove 18 are provided holes such as 20, whereby, when two similar panel frames are brought into vertical or superposed adjacent registry with each other, the ribs 19 of the upper frame will rest upon the ribs 16 of the lower frame, the grooves 15 and 18 will be in registry with each other, and the pins 17 of the lower frame will (because of their length and size) engage but not extend completely through the holes 20 of the upper frame, all to the end that the weight of the upper frame is borne by the side frame members 4 and 5 of the lower frame since said ribs are in the plane of the side frame members, and the engagement of the pins 17 with the holes 20 will prevent any lateral or transverse movement of one of the frames with respect to the other. The purposes of the grooves 15 and 18 will appear hereinafter.

When two similar panel frames are placed in sidewise registering adjacency, they are held together by a clip 10 engaging the grooves 8 in the webs 7 of the vertically contacting side frame members such as 4 of one frame and 5 of the adjacent frame. In addition, a positive lock may be provided between the adjacent frames by a tongue-like member, carried by one frame, adapted to co-engage a mortise or other opening in the adjacent frame, and in Fig. 3 one such locking means is particularly illustrated as comprising a dove-tail tenon 21 and a correspondingly shaped mortise 22. The tenon 21 projects from one end of the frame at substantially the middle of the top frame member 2 and disposed in the plane of the latter, the mortise 22 being formed in said frame member at the opposite end thereof, so that when two similar frames are brought together in sidewise relation, the tenon of the one frame will interlock with the mortise of the adjacent frame. Locking means of other shapes may be provided and disposed with respect to other frame members, as found desirable, but the same principle will be involved namely, the rigid interlock of two sidewise disposed frames to prevent any separating movement therebetween.

In Fig. 6 there is shown a portion of the joint between two vertically superposed frames, with a pin 17 of the lower frame disposed within the hole 20 of the upper frame, a glass block 25 being fragmentarily shown within the upper frame, and a similar glass block 26 within the lower frame, each glass block being of a depth or thickness greater than that of each frame so as to extend somewhat beyond the edge of the frame (indicated at 27) to provide a space or pocket 28 between the glass blocks beyond said edge. Most glass blocks on the market have a rabbet or shoulder construction such as 29 along each edge of a face thereof, and therefore such rabbet is utilized here for the reception of the longitudinal edge such as 30 of a locking strip generally identified by the numeral 31, by means of which the glass blocks may be prevented from slipping out of their frames. Said locking strip in transverse cross-section is shaped somewhat like a railroad rail, in that it is provided with a circular or bulb-like head 32 connected by a neck with oppositely extending flanges terminating in the longitudinal edges 30, said head extending inwardly into the space or pocket 28 between the blocks, and the flanges lying in the plane of the exposed vertical surfaces of the blocks, as clearly illustrated. Should it be desired to use glass blocks having no rabbet or shoulder along their edges, but rather having right-angled edges, the locking strips may be provided with a shoulder 33 formed adjacent their longitudinal edges as shown in Figs. 6a and

6b into which the corner edges of the blocks will fit.

A flat spring 35 is disposed in the groove 15 of the top frame member 2 of the lower frame, said spring apertured in order to accommodate closely the pins 17, and of a length such as to provide a free end portion 36 extending into the space 28 and formed with a curvature to snappingly engage and hold under tension the lower surface of the bulbous head 32 of the locking strip, it being understood that both ends of this spring are similarly formed if and when locking strips are desired on both faces of the panel, only one side portion of the panel being illustrated in Fig. 6. A similar flat spring 37 is provided in the groove 18 of the lower frame member 3 of the upper frame, but said spring is reversed (with respect to the spring 35) so that the free end portion 38 of spring 37 has its curvature presented to snappingly engage and hold under tension the upper surface of the bulbous head 32 of the locking strip, whereby said head will be engaged between the opposed ends 36 and 38 of said springs as clearly illustrated. The outermost edges of the spring ends may be curved or rounded as shown to permit the head of the locking strip to be pushed there-between into its locked position with respect to said springs, and the parts are so dimensioned that, when it is so locked, the longitudinal edges 30 of the locking strip will bear tightly against the surfaces of the corners of the glass blocks. The grooves 15 and 18 are of a depth to accommodate their respective springs, and the springs may be made of a thickness equal to or slightly greater than the depth of the grooves in which case the ribs 16 may be eliminated by widening the grooves so that the grooves or rabbets extend to the extreme edges of the frames, since vertically adjoining springs will be in surface contact with each other and, together with the vertical side members of the lower frames, provide a continuity of support for the weight of the upper frame or frames.

When a plate-like binder structure is to be disposed around a panel, or around an assembled plurality of panels as indicated in Fig. 1, the bottommost panel is provided with the spring 31 disposed in its groove 18, and the binder or plate 39 (see Fig. 9) is provided with pins such as 40 which are similar to the previously described pins 17 and for engaging the apertures of said spring and the bottom frame member 3 of said panel, it not being necessary to provide the second or lower spring (such as 35 shown in Fig. 6) because the plate 39 is provided with a rabbet surface 41 adapted to contact and support the lower surface of the bulb 32 of the locking strip 31. To prevent any turning movement of the locking strip, one of its longitudinal edges 30 has shouldered engagement with the corner or edge of the glass block such as 42, and the other longitudinal edge such as 43 of said strip overlaps and abuts the edge 44 of the plate 39, as clearly illustrated.

Whereas, in Figs. 6 and 9 there appears to be a space between the surface of a block and the inner surface of the frame holding said block, it is desired particularly to state that such space is exaggerated in the drawings due to the enlarged scale thereof, and that in actual practice such space will be extremely small and possibly there will be no space, since the panel frames are designed to receive their blocks in substantially close sliding fit.

From the foregoing description it will thus be understood that the locking strips 31, so far described, are positioned horizontally as indicated in

Fig. 1, serve to close the horizontal joints between the individual panels, and are of a length such that each strip is continuous from and including one vertical side 45 to and including the opposite vertical side 46 of the panelled construction. To close the vertical joints between each pair of horizontally adjacent glass blocks (such as 25 and 47, and 26 and 48), short locking strips such as 49 and 50 are employed, which are of the same cross-sectional size and shape as the horizontal locking strips 31, but each short locking strip is of a length just slightly greater than the distance between the facing flanges of two horizontal locking strips, as clearly illustrated in Fig. 8. No springs such as 35 and 37 are employed in the vertical joints between panels and hence, to secure these intercostal or short locking strips in place, the ends thereof in the region of their flanges are provided with a rabbet such as 51 so that, after the vertical short strips are placed in position with their flange edges engaging the corners of the horizontally adjacent glass blocks, the horizontal locking strip 31 may be springingly pressed into its locked position as hereinbefore described with the longitudinal edges of the strip 31 disposed within the rabbets 51 of the short strips. In other words, the extreme ends of the short vertical locking strips are locked or confined behind the longitudinal edges or flanges of the long horizontal locking strips, the rabbets 51 being of such depth as to cause the outer flat surfaces of all the locking strips to lie in a common plane substantially coincident with the plane of the exposed surfaces of the glass blocks so as to make a substantially smooth finished surface of the entire panelled wall construction.

Sealing compound may be employed or not employed as necessary, though obviously a weather-tight construction would be insured by its use in panels positioned in outer walls of a building. Where the panel construction is incorporated in inside building walls, the dimensions of the various parts of this invention may be so proportioned and related as to insure relatively close clearances such that the locking strips will hold the glass blocks substantially tight within their frames; the frames themselves are locked mechanically together as hereinbefore described.

Fig. 10 is more or less a composite of Figs. 6 and 9, but extended sidewise to show the duplication of the construction on the other side of the wall, and extended vertically to show the general relationship of two vertically adjacent blocks, the lowermost block being adjacent to a binding strip. In Fig. 10 the same reference numerals have been used as hereinbefore mentioned, but, in addition, primes have been added to the reference numerals of those parts of the construction which have been duplicated in the left hand portion of this figure. The numeral 60 indicates the building wall in which an opening is provided for the reception of the panel construction herein disclosed.

Thus there is provided a unitary panel comprising a frame, a building block and locking means therebetween, which may be used singly or in plural numbers to provide a wall section of any number of units and also of various shapes. In addition the unitary panels may be preassembled, placed in the plate-like binder such as 39 and then moved as a single entity to the job and erected in the wall with a minimum of labor cost and a considerable saving of time in the erection. When a single panel is to be used, as in new construction, it may be directly inserted in an opening provided therefor in the usual or existing wall, 75

whereupon the panel will fit the masonry wall surfaces defining such opening. When a single panel is required as a substitute for a damaged panel in a group or plurality of panels as illustrated in Fig. 1 (either before or after such group is incorporated in the building wall), or when a single panel is desired to enlarge an existing panel design or arrangement of a plurality of panels in a building wall, said single panel may be inserted in the opening provided therefor (either in the building wall or in the wall section comprised of the group of panels), and hence in these cases the wall surfaces defining such opening may comprise the masonry or other material of the building wall and/or the side members of the adjoining panels. Therefore, the constructions of Figs. 6 and 9 are instrumental in meeting these conditions of panel installations, and the similarity of these two constructions will be apparent in that the space or pocket 28 and the shoulders 29 of Fig. 6 have their substantial duplicates in Fig. 9; the parts 29 and 44 have the same function, wherefore the latter could be made identical to the former. Building blocks of glass or other material may be placed in the panel frames and should there be breakage of a block at any time, a new block may readily be replaced in the frame without dismantling the entire structure, by simply removing the necessary locking strips, extracting the broken block, putting the new block in, and reinserting the locking strips.

Therefore it will be seen that by this invention there is provided a wall construction involving the utilization of unitary panels, each panel comprising a frame and a building block therein, with a locking strip engaging an edge of said block, and yieldable means carried by said frame and engaging said locking strip whereby said strip secures said block in said frame. The block extends beyond an edge of said frame thereby to form with the edge of said frame a pocket, and the yieldable means is a spring having one portion recessed in and pinned to a surface of said frame and another or free end portion extending beyond the edge of said frame into said pocket and frictionally or springingly engaging the said locking strip, said strip comprising a bulbous portion extending into said pocket, and a longitudinally extending flange which engages the edge of said block. The grooves formed in the surfaces of the panel frame are similarly shaped and similarly positioned so that when two frames are juxtaposed the grooves thereof will be in registry and by utilizing complementally formed holding means such as the pins 17 and holes 29, or the tenons 21 and the mortises 22, the frames will be secured against relative movement therebetween.

It is obvious that those skilled in the art may vary the details of construction and arrangements of parts without departing from the spirit of this invention, and therefore it is desired not to be limited to the exact foregoing disclosure except as may be required by the claims.

What is claimed is:

1. In wall construction, a plurality of similarly formed and juxtaposed panels secured together, each panel comprising a polygonal frame and a building block therein, said frame having a groove formed transversely thereof in the outer surface of one frame-side with a pin projecting outwardly of said groove from the bottom thereof, said frame having another similarly shaped and positioned groove formed in the outer surface of an opposite frame-side with a recess extending from the bottom of such groove inwardly of such opposite

frame-side whereby the groove of one frame registers with the groove of the adjacent frame with the pin of the former extending into the recess of the latter to prevent relative movement between the frames, a locking strip closing the joint between the blocks in two juxtaposed frames, said strip engaging the adjacent edges of the blocks in such juxtaposed frames, and anchor means disposed in the registered grooves of such juxtaposed frames and secured therein by said pin and having opposed socket-forming free ends yieldably engaging a complementally formed headed portion of said locking strip to hold said block in said frame.

2. In wall construction, wall surfaces defining an opening in the wall; a frame closely fitting such wall surfaces and comprising side members rigidly secured together at their ends to provide a unitary structure, the outer surface of a side member adjacent an end thereof provided with a recess extending transversely of the side member; a leaf-like spring having one portion rigidly secured in said recess and another portion extending beyond the edge of said side member, the extending portion having a socket-like formation yieldably engageable with a locking strip; a building block closely fitting the inner surfaces of said frame but of a thickness such that the block extends beyond an edge of said frame; and a locking strip securing said block in said frame, said locking strip substantially coextensive with the wall opening and having opposed flange portions one engaging an edge of said block and the other engaging an edge of the wall opening, said strip also having a headed portion projecting in a direction toward the edge of the frame, said headed portion of a shape complemental to and engaged by the socket-like extending portion of said spring thereby providing a readily engageable and disengageable lock between said strip and said spring.

3. In wall construction, wall surfaces defining an opening in the wall; a frame closely fitting such wall surfaces and comprising side members joined together at their ends to provide a relatively unitary structure; a leaf-like spring having one portion anchored to an exterior surface of a side member of said frame and having another portion extending beyond the edge of said side member, the extending portion having a socket-like formation yieldably engageable with a locking strip; a building block closely fitting the inner surfaces of said frame but of a thickness such that the block extends beyond an edge of said frame; and a locking strip for securing said block in said frame, said locking strip substantially coextensive with the wall opening and having opposed flange portions one engaging an edge of said block and the other engaging an edge of the wall opening, said strip also having a headed portion projecting in a direction toward the edge of the frame, said headed portion of a shape complemental to and engaged by the socket-like extending portion of said spring thereby providing a readily engageable and disengageable lock between said strip and said spring.

4. In wall construction, a panel comprising a frame and a building block having slidable engagement therein, a recess formed in an exterior surface of said frame, a locking strip engaging an edge of said block and having a portion adapted to interlock with an anchor means, and anchor means having one portion secured

in said recess and having another portion comprising a yieldable free end formed complementally to and engaging the interlocking portion of said locking strip to hold said block in said frame.

5. For wall construction, a plurality of similarly formed and juxtaposed panels secured together, each panel comprising a polygonal frame and a building block therein, said frame having a groove formed transversely thereof in the outer surface of one frame-side with a pin projecting outwardly of said groove from the bottom thereof, said frame having another similarly shaped and positioned groove formed in the outer surface of an opposite frame-side with a recess extending from the bottom of such groove inwardly of such opposite frame-side whereby the groove of one frame registers with the groove of the adjacent frame with the pin of the former extending into the recess of the latter to prevent relative movement between the frames, a locking strip closing the joint between the blocks in two juxtaposed frames, said strip engaging the adjacent edges of the blocks in such juxtaposed frames, and anchor means disposed in the registered grooves of such juxtaposed frames and secured therein by said pin and having opposed socket-forming free ends yieldably engaging a complementally formed headed portion of said locking strip to hold said block in said frame.

6. A wall section comprising a frame and a building block having slidable engagement therein, a binder structure disposed about said frame, a locking strip engaging an edge of said block as well as an edge of said binder structure and having a portion constituting one-half of a means holding said block in said frame, and yieldable means having one portion secured in a recess formed in an exterior surface of said frame and having another portion constituting the other half of the block-holding means, the said other portion extending beyond the edge of said frame and interfitting said portion of said locking strip to hold said block in said frame.

7. A wall section comprising a frame and a building block having slidable engagement therein, an exterior surface of said frame having a recess formed therein, a binder structure disposed about said frame, a locking strip engaging an edge of said block as well as an edge of said binder structure and having a portion constituting one-half of a means holding said block in said frame, and a spring having one portion secured in said recess and having another portion constituting the other half of the block-holding means, the said other portion extending beyond the edge of said frame and interfitting said portion of said locking strip to hold said block in said frame.

8. A wall section comprising a frame and a building block having slidable engagement therein, a binder structure disposed about said frame, a locking strip comprising a headed portion and longitudinally extending flanges the latter engaging an edge of said block as well as an edge of said binder structure, and yieldable means having one portion recessed in and secured to an exterior surface of said frame and having a socket-like portion extending beyond the edge of said frame and frictionally receiving therein the headed portion of said locking strip to hold said block in said frame.

9. A wall section comprising a frame and a building block having slidable engagement there-

in, said block extending beyond an edge of said frame thereby to form with the frame edge a pocket, an exterior surface of said frame having a groove formed transversely thereof, a binder structure disposed about said frame, a locking strip having a headed portion disposed in such pocket and having flanged portions engaging an edge of said block as well as an edge of said binder structure, and anchor means having one portion secured in said groove and having a yieldable socket-like portion extending into such pocket and interlocked with the headed portion of said locking strip to hold said block in said frame.

10. In wall construction, a panel comprising a frame and a building block having slideable engagement therein, a recess formed in an exterior surface of said frame, a locking strip engaging an edge of said block and having a portion adapted to interlock with an anchor means, and anchor means having one portion secured in said recess and having another portion comprising a free end formed complementally to and engaging the interlocking portion of said locking strip to hold said block in said frame.

11. A wall section comprising a frame and a building block having slideable engagement therein, a binder structure disposed about said frame, a recess formed in an exterior surface of said frame and a pin projecting into said recess from a wall thereof, a locking strip engaging an edge of said block as well as an edge of said binder structure and having a portion adapted to interlock with an anchor means, and anchor means secured in said recess by said pin and having a socket-like portion extending beyond the edge of said frame, said socket-like portion formed complementally to and engaging the interlocking portion of said locking strip to hold said block in said frame.

12. A wall section comprising a plurality of similarly formed and juxtaposed panels, each panel comprising a polygonal frame and a building block therein, said frame having similarly shaped and positioned grooves formed transversely in the outer surfaces of opposing sides thereof and having complementally formed hold-

ing means whereby the grooves of the juxtaposed frames are in registry and the frames are secured by such holding means against relative movement therebetween, a locking strip closing the joint between the blocks in two juxtaposed frames, said locking strip having a portion adapted to interlock with an anchor means, said locking strip engaging the adjacent edges of the blocks in such juxtaposed frames, and anchor means disposed in the registered grooves of such juxtaposed frames and secured therein by said holding means, said anchor means having a free end formed complementally to and engaging the interlocking portion of said locking strip to hold said block in said frame.

15. 13. A wall section comprising a plurality of similarly formed and juxtaposed panels, each panel comprising a polygonal frame and a building block therein, said frame having similarly shaped and positioned grooves formed transversely in the outer surfaces of one pair of opposed sides thereof and having complementally formed holding means whereby the grooves of two frames juxtaposed in one direction are in registry and these frames are secured against relative movement therebetween, said frame also having a locking means disposed in the plane of one of its sides and which coengages with a complementally formed locking means of a frame juxtaposed in another direction thereby securing these frames together, long and short locking strips closing the joints between the blocks in juxtaposed frames, a long locking strip having a portion adapted to interlock with an anchor means, said strips engaging the adjacent edges of the blocks in such juxtaposed frames, and anchor means disposed in the registered grooves of the first mentioned juxtaposed frames and secured therein by said holding means, said anchor means having a free end formed complementally to and engaging the interlocking portion of such long locking strip, a short locking strip extending in a direction transverse to a long locking strip and having its opposite ends retained by the facing edge portions of two adjacent long locking strips.

GEORGE H. LENKE.
